UNITED STATES PATENT OFFICE.

ALEXANDER ST. CLAIRE, OF LOS ANGELES, CALIFORNIA.

LIGHT INDICATOR FOR REFLECTOR LAMPS.

Application filed September 14, 1925. Serial No. 56,198.

This invention is applicable to various uses, but is more particularly intended for use on headlight and tail light lamps for motor vehicles.

- 5 An object of this invention is to provide a device, which is easily applied to the lamps of automobiles and the like to enable the driver or user of the light to be constantly advised as to whether the light is or is not lit.
10 In carrying out this invention I provide holes in the lamp reflector and housing or body and mount a translucent lens in the hole in the housing or body.

The lens, the holes and the luminary are arranged sufficiently in line with each other so that the light rays from the luminary will illuminate the lens to let the driver of the vehicle see whether or not the light is lit.

An object is to provide a cheap and simple device of this character, that can be applied from the outside to lamps now in use, as well as in the original manufacture of the lamp.

In carrying out this invention, I provide a bushing adapted to carry a translucent lens in one end and adapted to be inserted through a hole in the lamp housing or body and to be held tightly therein without disturbing the inner mechanism of the lamp, and which will be illuminated whenever the lamp is lit.

Other objects, advantages and features of invention may appear from the accompanying drawing, the subjoined detailed description and the appended claims.

The accompanying drawing illustrates the invention in the form at present deemed most desirable.

Figure 1 is a view of the rear of a reflector lamp supplied with my invention and mounted on an automobile, a fragment of which is shown.

Fig. 2 is a view of the invention on a larger scale applied to a reflector lamp which is mainly shown in vertical axial section.

Fig. 3 is a rear end view of the device on a larger scale and constructed in accordance with this invention.

Fig. 4 is a side elevation of the device shown in Fig. 3.

Fig. 5 is a view of the inside and of the invention shown in the previous views.

Fig. 6 is an elevation mainly in longitudinal section on line $\alpha\alpha$, Fig. 5.

55 Fig. 7 is a detached view of the lens holder.

The housing or body 1 may be of any usual construction and may contain the usual reflector 2 and luminary 3.

The housing is shown provided with a hole 4, and the reflector with a hole 5; the holes 4 and 5 may be alined with the luminary 3, or alined as shown in Fig. 2.

6 is a tubular bushing, which may be made of brass or any other suitable material, and is expanded at 7 to form a seat 8 for the lens 9 which may be of glass or other translucent material, and of red or green or any other color determined upon.

The lens is held in the seat 8 by the edges 10 of the seat clamped over the rim of the lens.

The bushing is provided with tongues 12 struck out from the walls of the bushing and adapted to serve as retainers for a locking plate 13 which is yieldingly held toward the inner end of the bushing by a spring 14, which in turn is held by the cap 15.

Said cap 15 has side walls 16 telescoping with like walls 17 of the locking plate 13, and the spring 14 is enclosed within the telescoping walls of the cap 15 and the locking plate 13; the spring at all times tending to force cap 15 and locking plate 17 apart.

The spring 14 is adapted to allow the cap and locking plate to telescope sufficiently to accommodate the thickness of the lamp body or housing 1 between said locking plate and the projecting ends of the tongues or retainers 12 when the tube 6 is inserted into the lamp body 1. The resiliency of the spring forcing the locking plate against the lamp body on one side, and the cap bearing against the expanded portion of the tube at 7, tends to withdraw the tube 6 through the hole 4, and this causes the ends of the retainers 12 to bear against the inner wall of the lamp body, so that the device is securely in place.

I claim:

1. The lamp indicating appliance set forth comprising a bushing provided with a translucent lens and with retainers adapted to engage a lamp casing through which the bushing may be inserted; a locking plate and cap telescoping with each other on the bushing; and means to yieldingly hold the cap and locking plate apart.

2. The combination with a reflector lamp casing; of a light indicating appliance, comprising a bushing adapted to be inserted through a hole in the casing and having one end expanded to form a seat; a translucent

lens in said seat; a locking plate and a cap telescopically connected, said plate and cap being disposed between the casing and the expanded end of said bushing; retainers on the bushing, and a spring to hold the cap toward the retainers to clasp the casing.

3. The combination with a reflector lamp casing; of a tube adapted to be inserted through an opening in the lamp casing; a translucent lens connected to the outer end of said tube, said tube being provided with resilient tongues struck out therefrom; a cap on said tube; means to retain the cap on the tube; a locking plate on said tube telescoping with the cap and being retained by the tongues; and a spring between the cap and the locking plate to hold the locking plate toward the cap for the purpose of engaging the casing.

4. The combination with a reflector lamp casing; of a light indicating attachment com-

prising a tubular member adapted to be passed through an opening in the lamp casing, said tubular member having an expanded end portion formed with a flange; a translucent lens mounted on the expanded end portion of said tubular member and being retained in position by said flange; a cap and locking plate mounted on said tubular member between said expanded end of said member and casing; resilient tongues struck out from said tubular member and adapted for engagement with said lamp casing, when the tube is inserted through the opening therein, and a spring interposed between said cap and locking plate for urging the said tubular member outwardly to hold said tongues in engagement with the lamp casing.

In testimony whereof, I have hereunto set my hand at Los Angeles, California, this 4th day of September 1925.

ALEXANDER ST. CLAIRE.
